COIN-OPERATED ELECTRIC IRON

Harry S. Kaufman, San Diego, Calif.

Application March 11, 1946, Serial No. 653,611

2. Claims. (Cl. 194—84)

1.

My invention relates to a coin operated electric iron, more particularly an improvement over my patent application, Serial Number 622,189, filed October 13, 1945, now abandoned, and the objects of my invention are:

First, to provide a coin operated electric iron of this class in which the coin operated control is readily removably connected to the iron with which it is used.

Second, to provide a coin operated electric iron of this class in which the coin operated control means may be plugged in connection with the conventional plug receiving prongs of conventional electric irons.

Third, to provide a coin operated electric iron of this class which is very compact and unobtrusive.

Fourth, to provide a coin operated electric iron of this class in which a pair of rotating coin receiving plates are directly connected with the time clock shaft providing a very simple and compact structure which does not hamper the operations of the person ironing clothes or the like therewith.

Fifth, to provide a coin operated electric iron of this class in which a guard plate covers the coin receiving plates when in operation preventing the coin receiving plates from being tampered with, and;

Sixth, to provide a coin operated electric iron of this class which is very simple and economical of construction, efficient in operation and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon forming a part of this application in which:

Figure 1 is a top or plan view of my coin operated electric iron; Figure 2 is a vertical sectional view taken from the line 2—2 of Fig. 1 showing parts and portions in elevation to facilitate the illustration; Figure 3 is a fragmentary sectional view taken from the line 3—3 of Fig. 2; Figure 4 is a fragmentary sectional view taken from the line 4—4 of Fig. 2; Figure 5 is a fragmentary sectional view taken from the line 5—5 of Fig. 2; Figure 6 is a fragmentary sectional view taken from the line 6—6 of Fig. 2; Figure 7 is a fragmentary sectional view taken from the line 7—7 of Fig. 2; and Figure 8 is a diagram-

2.

matic view of the wiring used in connection with my coin operated electric iron.

Similar characters of reference refer to similar parts and portions throughout the several views of the drawings.

The casing 1, casing cover 2, time clock 3, electrical contacts 4 and 5, cam 6, time clock shaft 7, coin receiving plates 8 and 9, guard plate 10, control knob 11, lock 12, spring 13, and the lock plate 14 constitute the principal parts and portions of my coin operated electric iron.

The casing 1 is provided with a prong engaging plug portion 1a, removably positioned in the plug frame 1b, of the conventional electric iron 1c, all as shown best in Fig. 1 of the drawings.

The casing 1 is also provided with a control casing portion 1d in which the time clock 3 is positioned. The time clock 3 is a conventional timing device, having an escapement mechanism and a main spring shaft, designated the time clock shaft 7. It will be noted that the casing 1, at its control casing portion 1d, is enclosed by the casing cover 2 which is secured, in connection with the casing 1, by means of a conventional tumbler lock 12 connected with the cover 2 as shown best in Figs. 3 and 7 of the drawings.

This tumbler lock 12 is provided with a locking lug 12a as shown best in Fig. 2 of the drawings, adapted to be positioned through the opening 14a in the lock plate 14 which is secured to the plug receiving frame portion 1b of the iron 1c. The opening 14a accommodates the insertion of the locking lug 12a of the tumbler lock 12 which, when rotated 90°, engages the normally rear side of the lock plate 14, securing the cover 2 in connection with the casing 1 and maintaining the plug portion 1a of the casing 1 in the plug receiving frame 1b of the iron 1c. The electrical contacts 4 and 5, as shown in Fig. 7 of the drawings, are secured in connection with the time clock 3 by the bracket 3a and these contacts 4 and 5 are electrically secured to conductors 4a and 5a, as shown in the diagrammatic view of the wiring in Fig. 8 of the drawings. The electrical contact 4 is engageable with the cam member 6 secured on the guard plate 10, rotatably mounted about the axis of the shaft 7. As shown in Fig. 2 of the drawings, the coin receiving plate 8 is positioned intermediate the coin receiving plate 9 and the guard plate 10. The coin receiving plate 9 is provided with a coin receiving recess portion 9a in its side, adjacent the coin receiving plate 8. The coin receiving plate 8 is provided with a coin receiving slot 8a adjacent the coin receiving plate 9. It will be noted that the shaft

7 is provided with flats 7a thereon on which the coin receiving plate 8 is fixed. The coin receiving plate 9 is rotatably mounted on the shaft 7. The guard plate 10, together with the cam 6, is freely rotatably mounted on the shaft 7 as shown in Fig. 6 of the drawing. The coin receiving plate 9 is provided with an integral extending shaft portion 9b, having a hub portion 9c engaged by the spring 13. This spring 13 is secured at its opposite end 13a to the inner side of the casing cover 2 as shown best in Fig. 3 of the drawings. Tension of the spring 13 tends to hold the coin receiving plate 9 in approximately the position as shown in Fig. 4 of the drawings, wherein, the recess portion 9a is open at the upper peripheral edge of said coin receiving plate 9. This recess 9a cooperates with the recess 8a in the coin receiving plate 8 for receiving coins. The depth of the recess 9a is substantially one-half of the thickness of the coin to be received thereby. The recess 8a, in the coin receiving plate 8, is deep enough to receive the other half of the coin, positioned at one side in the coin receiving recess 9a of the coin receiving plate 9. The coin recess 8a, in the coin receiving plate 8, is substantially U-shaped and communicates with the periphery thereof while the recess 9a, in the coin receiving plate 9, is defined by a semi U-shaped portion having a cordially disposed, gradually curved edge communicating with the closed side of said semi U-shaped recess portion. The coin receiving plate 8 is provided with a laterally extending tab portion 8b engageable with the radially extending step portions 10a and 10b of the guard plate 10 when rotated substantially 180°. The guard plate 10 is provided with a laterally extending arcuate guard portion 10c which extends over the upper edges of the coin receiving plates 8 and 9 as shown best in Fig. 2 of the drawings. Secured to one side of this guard plate 10 is the cam 6 which engages the contact 4 which is provided with a resilient arm 4b, similar to the resilient arm 5b of the contact 5. The contacts 4 and 5 are normally open contacts and are held in closed position as shown in Fig. 7 by the cam 6. The control knob 11 is secured on the shaft portion 9b in connection with the coin receiving plate 9 and is used in the manual setting of my coin operated electric iron. It will be here noted that the casing cover 2 is provided with a slotted portion 2a in its normally upper side, arranged to receive coins placed in the recess portion 8a and 9a of the coin receiving plates 8 and 9. This casing cover 2 is also provided with a channel portion 2b directly below the slotted portion 2a, arranged to convey coins downwardly into the coin receiving recess portion 1e as shown best in Fig. 2 of the drawings.

The operation of my coin operated electric iron is substantially as follows:

When the coin receiving plates 8 and 9 are in the positions as shown in Figs. 4 and 5 of the drawings the escapement mechanism in the time clock 3 permits the shaft 7 to rotate slowly in the direction as indicated by the arrow "A" in Fig. 5 of the drawings, carrying with it the coin receiving plate 8. When the recess portion 8a, of the coin receiving plate 8, reaches the slotted portion 2a, of the casing cover 2, the tab portion 8b, of the coin receiving plate 8, engages the ledge portion 10b, of the guard plates 10 and forces the same in the direction as indicated by the arrow "B" in Fig. 6 of the drawings. When forced in the direction as indicated by the arrow "B" in Fig. 6 of the drawings, the cam 6 in connection

with the guard plates 10 passes the contact member 4 at its apex portion 6a, whereupon, the resilient thrust of the contacts 4 and 5 and the angular side 6b of the cam 6 rotates the arcuate guard portion 10c away from the opening 2a in the casing cover 2. It will be noted that during rotation of the shaft 7 together with the coin receiving plate 8 and movement of the guard plate 10, that the coin receiving plate 9 remains in the position as shown in Fig. 4 of the drawings maintained by the spring 13 due to the freely revoluble relation of the shaft 7 in the coin receiving plate 9. When the recess portion 8a, of the coin receiving plate 8, indexes with the coin receiving opening 9a, of the coin receiving plate 9, directly below the opening 2a, in the casing cover 2, a coin may be inserted intermediate the coin receiving plates 8 and 9 in the recess portions 8a and 9a thereof. It will be noted that a coin inserted in the recesses 8a and 9a extends half of its thickness into the recess 8a and the other half of its thickness into the recess 9a in the coin receiving plates 8 and 9 respectively. When the coin is in place in the recesses 8a and 9a the control knob 11 may be turned in a clockwise direction carrying with it the coin receiving plate 9 and the coin receiving plate 8 interlocked to the coin receiving plate 9 by the coin in the recess portions 8a and 9a. The control knob 11 is turned in a clockwise direction, as shown in Fig. 5 of the drawings, until the recess portion 8a assumes the position, as shown in Fig. 5 of the drawings, above the coin receiving channel 2b, of the casing cover 2. As the coin receiving plate 8 is rotated in a clockwise direction the shaft 7 secured in connection therewith is turned therewith with winding the spring motor in the time clock 3, whereupon, the escapement mechanism is started. It will be noted that the cordially disposed curved portion of the recess 9a, in the coin receiving plate 9, during return rotational movement, ejects the coin in the recesses 8a and 9a downwardly into the coin receiving channel 2b of the casing cover 2. When the control knob 11 is released the spring 13 returns the coin receiving plate 9 to the position as shown in Fig. 4 of the drawings. Coins are conveyed in the recesses 8a and 9a, of the coin receiving plates 8 and 9, dropped through the channel 2b, in the casing cover 2, and are contained in the recess 1e, of the casing 1, until collected. It will be noted that when the coin receiving plate 8 is turned to the position, as shown in Fig. 5 of the drawings, the tab portion 8b of said coin receiving plate 8, engages the ledge portion 10a, of the guard plate 10, and forces the same into the solid line position as shown in Fig. 5 of the drawings, wherein, the apex 6a, of the cam 6, forces the contact 4 into engagement with the contact 5, closing the electrical circuit as shown in Fig. 8 of the drawings. These contacts 4 and 5 remain in closed position until the escapement mechanism in the time clock 3 permits the shaft 7 to rotate in the direction as indicated by the arrow "A" in Fig. 5 of the drawings, until the recess 8a is again in the upper vertical position wherein the tab portion 8b again engages the ledge portion 10b, of the guard plate 10, and this disengages the apex 6a, of the cam 6, from the contacts 4 and 5 permitting the same to open, whereupon, another coin must be inserted to continue electrical operation of the electrical iron 1c. Time interval involved may be varied as desired by the particular escapement used in the time clock 3, however, the time clock as shown rotates

the recess $8a$ from the position as shown in Fig. 5 of the drawings, to a position indexed with the slotted portion $2a$, of the casing cover 2, within approximately thirty minutes. When it is desired to collect the coins accumulated in the recess $1e$ of the casing 1, the tumbler lock 12 is opened in the conventional manner by the use of a key and the locking lug 12a is turned substantially 90° to index with the slotted portion 14a, in the lock plate 14, whereupon, the cover 2, together with the control knob 11, coin receiving plate 9 and the spring 13 may be removed from the casing 1. The coins may then be removed from the recess 1e and the cover 2 may be replaced and locked into position by means of the tumbler lock 12. It will be noted that the lock plate 14 extends into a slotted portion 1f, in the casing 1, and that the engagement of the lock 12 with the lock plate 14 prevents removal of the plug portion 1a, of the casing 1, from the plug receiving frame 1b of the electric iron 1c. In the diagrammatic view of the wiring, in Fig. 8 of the drawings, the electrical conductors 4a and 5a, as shown in Fig. 7 of the drawings, are in circuit with one of the conventional electric iron plug prongs 1g, electrically connected to the heating element 1h connected at its opposite end to the plug prong 1j electrically connected to one wire 1k of the cord 1m all as shown best in Figures 1 and 8 of the drawings.

Though I have shown and described a particular construction, combination and arrangement of parts and portions, I do not wish to be limited to the particular construction, combination and arrangement but desire to include in the scope of my invention the construction, combination and arrangement substantially as set forth in the appended claims.

Having thus described my invention, what I claim as new and desire to secure by Letters Patent is:

1. In a coin controlled electric iron of the class described, the combination of a casing, a time clock mounted in said casing having an extended shaft, a guard plate freely rotatable on said shaft, a cam in connection with said guard plate, a pair of electrical contacts engageable with said cam, a first coin receiving plate fixed on said shaft and having a coin receiving recess therein, at one side thereof, equal to approximately one-

half the thickness of a coin to be inserted therein, a second coin receiving plate rotatably mounted relatively to said shaft and having a coin receiving recess in one side thereof adjacent said first receiving plate, said recess in said second coin receiving plate being of a depth substantially one-half the thickness of a coin to be inserted therein, said first mentioned coin receiving plate having a tab portion engageable with said guard plate, whereby rotation of said first coin receiving plate engages said tab portion with said guard plate causing said cam to close said contacts.

2. In a coin controlled electric iron of the class described, the combination of a casing, a time clock mounted in said casing having an extended shaft, a guard plate freely rotatable on said shaft, a cam in connection with said guard plate, a pair of electrical contacts engageable with said cam, a first coin receiving plate fixed on said shaft and having a coin receiving recess therein, at one side thereof, equal to approximately one-half the thickness of a coin to be inserted therein, a second coin receiving plate rotatably mounted relatively to said shaft and having a coin receiving recess in one side thereof adjacent said first receiving plate, said recess in said second coin receiving plate being of a depth substantially one-half the thickness of a coin to be inserted therein, said first mentioned coin receiving plate having a tab portion engageable with said guard plate, whereby rotation of said first coin receiving plate engages said tab portion with said guard plate causing said cam to close said contacts.

3. In a coin controlled electric iron of the class described, the combination of a casing, a time clock mounted in said casing having an extended shaft, a guard plate freely rotatable on said shaft, a cam in connection with said guard plate, a pair of electrical contacts engageable with said cam, a first coin receiving plate fixed on said shaft and having a coin receiving recess therein, at one side thereof, equal to approximately one-half the thickness of a coin to be inserted therein, a second coin receiving plate rotatably mounted relatively to said shaft and having a coin receiving recess in one side thereof adjacent said first receiving plate, said recess in said second coin receiving plate being of a depth substantially one-half the thickness of a coin to be inserted therein, said first mentioned coin receiving plate having a tab portion engageable with said guard plate, whereby rotation of said first coin receiving plate engages said tab portion with said guard plate causing said cam to close said contacts.

4. In a coin controlled electric iron of the class described, the combination of a casing, a time clock mounted in said casing having an extended shaft, a guard plate freely rotatable on said shaft, a cam in connection with said guard plate, a pair of electrical contacts engageable with said cam, a first coin receiving plate fixed on said shaft and having a coin receiving recess therein, at one side thereof, equal to approximately one-half the thickness of a coin to be inserted therein, a second coin receiving plate rotatably mounted relatively to said shaft and having a coin receiving recess in one side thereof adjacent said first receiving plate, said recess in said second coin receiving plate being of a depth substantially one-half the thickness of a coin to be inserted therein, said first mentioned coin receiving plate having a tab portion engageable with said guard plate, whereby rotation of said first coin receiving plate engages said tab portion with said guard plate causing said cam to close said contacts.

5. In a coin controlled electric iron of the class described, the combination of a casing, a time clock mounted in said casing having an extended shaft, a guard plate freely rotatable on said shaft, a cam in connection with said guard plate, a pair of electrical contacts engageable with said cam, a first coin receiving plate fixed on said shaft and having a coin receiving recess therein, at one side thereof, equal to approximately one-half the thickness of a coin to be inserted therein, a second coin receiving plate rotatably mounted relatively to said shaft and having a coin receiving recess in one side thereof adjacent said first receiving plate, said recess in said second coin receiving plate being of a depth substantially one-half the thickness of a coin to be inserted therein, said first mentioned coin receiving plate having a tab portion engageable with said guard plate, whereby rotation of said first coin receiving plate engages said tab portion with said guard plate causing said cam to close said contacts.

6. In a coin controlled electric iron of the class described, the combination of a casing, a time clock mounted in said casing having an extended shaft, a guard plate freely rotatable on said shaft, a cam in connection with said guard plate, a pair of electrical contacts engageable with said cam, a first coin receiving plate fixed on said shaft and having a coin receiving recess therein, at one side thereof, equal to approximately one-half the thickness of a coin to be inserted therein, a second coin receiving plate rotatably mounted relatively to said shaft and having a coin receiving recess in one side thereof adjacent said first receiving plate, said recess in said second coin receiving plate being of a depth substantially one-half the thickness of a coin to be inserted therein, said first mentioned coin receiving plate having a tab portion engageable with said guard plate, whereby rotation of said first coin receiving plate engages said tab portion with said guard plate causing said cam to close said contacts.
